TURNING ATTACHMENT FOR TILES
Melville Keim, Highland Park, Ill.
Application July 20, 1953, Serial No. 369,090
5 Claims. (Cl. 273—136)

This invention relates to a device for reversing the positions of loose tiles and the like and it relates more particularly to an attachment for use in combination with a playing board for games and the like which make use of tiles that are placed in one position on the board but which must be turned over to be face down or the like at the start of each game, and it is an object of this invention to produce a device of the type described.

More specifically, it is an object of this invention to produce an attachment for use in combination with playing boards for reversing tiles or other objects on the surface of the board in a simple and efficient manner and it is a related object to embody means in a device of the type described for supporting the board in proper position in operative engagement with the device properly to position the elements for effecting substantially complete reversal of the tiles on the surface of the board.

These and other objects and advantages of this invention will hereinafter appear and for purposes of illustration, but not of limitation, embodiments are shown in the accompanying drawing in which:

Figure 1 is a schematic elevational view of an attachment embodying features of this invention;

Figure 2 is a perspective view of the attachment shown in Figure 1 in position of use with the playing board;

Figure 3 is a sectional elevational view of the attachment in position of use on the playing board prior to positioning for reversal of tiles;

Figure 4 is a sectional view corresponding to that of Figure 3 but with the elements tilted to a desired angle for tile reversal;

Figure 5 is a perspective view of a modified form of an attachment embodying features of this invention, and

Figure 6 is a sectional view corresponding to that of Figure 3 with a modified form of the attachment.

Briefly described, an attachment embodying features of this invention comprises a pair of vertically positioned plates 10 and 11 formed of wood, plastics, metal or other similar rigid material and spaced apart by an amount less than the distance between edges of the board 12 with which the attachment is used. Each plate 10 and 11 is formed with a slot 13 dimensioned to have a width greater than the thickness of the board and extending inwardly from the forward edge from an intermediate portion thereof for a distance adapted to receive an edge portion of the board therein for establishing a desired mounted relation.

Interconnecting the plates 10 and 11 in the desired spaced relation is a deflector wall 14 in the form of a strip of sheet metal, plastics or the like preferably attached to the rearward edge portion of the plates for cooperation with the board to control turning movement of the tiles 15 and for laying the tiles gently on the top of the table 16 and onto other supporting surfaces. The deflector wall portion in alignment with the slots is spaced from the rearward edge of the slots by a distance greater than one-half the length or width of the tiles and preferably less than the full lengths thereof and the lower-edge portion 17 of the wall is formed curvilinear preferably through an arc corresponding to the angle of tilt of the board in use. Generally a tilt of between 35 and 55 degrees will be sufficient for gravitational movement of the tiles over the surface of the board. The back wall of the deflector may be formed curvilinear, as illustrated in Figures 1-5 inclusive, or it may be formed relatively straight, as indicated by the numeral 18 in

2

Figure 6 with an arcuate lower edge portion 19 as described.

In operation, when it is desired to turn the tiles 15 face down for the start of a new game, an edge of the board 12 is inserted into the slots 13 and the board is tilted upwardly with the attachment resting on the surface of the table 16. When the board has been tilted to a desired angle, the tiles would begin to slide down the surface of the board and over the lower edge. When more than one-half of the tile extends beyond the lower edge of the board, the center of gravity will cause the tile to turn and flip over as it drops through space and into the lower portion of the turner wall which guides the tiles face down on the underlying surface of the table. Since the distance between the edge of the board and the deflector wall in alignment therewith is greater than one-half but less than the full lengths of the tiles, movement of the tiles is arrested while the rearward edge portion remains in sufficient contact with the edge of the board to insure engagement therewith as the center of gravity extends beyond the edge so as to insure the desired flip-over.

For best results, it is expedient to move the board slowly in the direction of tilt so that interference between tiles will be avoided and the tiles caused to form a uniform layer face down on the table top. For this purpose, it is desirable to provide a felt 20 or other soft material about the edges of the plates in contact with the table top and also to provide a similar soft or resilient material as a lining 21 in the slots for enabling a better gripping relation to be established with the edges of the boards in position of use.

It will be apparent that the back wall of the deflector need not be formed curvilinear when the desired spaced relation exists and it will be equally evident that the deflector may be formed with a top wall to cover the edge of the board when in mounted relation without interfering with the operation thereof. In fact, when a top wall is formed integral with the back wall to conceal the edge of the board, the turning action provides an additional amusement feature in itself by its turning action.

When the playing board is formed with one or more folds for collapsing the board during non-use, it is necessary to provide means which prevents deflection in the foldable portion during use of the attachment, otherwise the described spaced relation with the edge of the board and the turning wall cannot be maintained with the result that the tiles will not be turned over onto the opposite sides. To prevent improper alignment in the mounted relation, the modification shown in Figure 5 embodies a supporting element in the form of a rod 22 extending between the side plates 10 and 11 in closely spaced relation with the underside and adjacent the forward edge of the slots 13. The rod supports the underside of the board when the latter is inserted in position of use in the slot to prevent deflection in the downward direction of any portion between the plates.

It will be evident that the turning attachment described is adaptable for use with other operable surfaces to effect reversal of position of elements on the face thereof and that an attachment of the type described can provide a game in itself because of its turning action in use.

It will be understood that changes may be made in the details of construction, arrangement and operation and in the materials of which the attachment is formed without departing from the spirit of the invention, especially as defined in the following claims.

I claim:

1. An attachment for use in combination with a board for inverting elements of uniform dimension having flat top and bottom faces upon displacement of the elements over the surface of the board onto a table by tilting, comprising laterally spaced and vertically disposed rigid supports having slots extending inwardly from a forward edge intermediate the ends having a thickness adapted to receive the edge of the board therein, a deflector wall interconnecting the supports and spaced from the rearward edge of the slots by a distance greater than one-half but less than the maximum dimension of the top and bottom surfaces of the elements on the surface of

the board, said deflector wall having a lower edge portion of curvilinear shape which is disposed substantially horizontally when the board is tilted to displace the elements downwardly over the surface thereof towards the attachment.

2. An attachment as claimed in claim 1 in which the support is formed with a curvilinear rear wall upon which the support is rocked between tilted and horizontal positions.

3. An attachment as claimed in claim 1 in which the deflector wall is curvilinear from the bottom edge to the top.

4. An attachment as claimed in claim 1 in which the

supports are lined with a soft and resilient material on the exposed edge portions.

5. An attachment as claimed in claim 1 in which a rod extends transversely between the supports closely adjacent the forward edge and beneath the slots.
